US00D998453S

(12) **United States Design Patent** (10) **Patent No.:** **US D998,453 S**
(45) **Date of Patent:** **** Sep. 12, 2023**

(54) **PORTION CAPSULE**

(71) Applicant: **K-FEE SYSTEM GMBH**, Bergisch Gladbach (DE)

(72) Inventor: **Marc Krüger**, Bergisch Gladbach (DE)

(73) Assignee: **K-FEE SYSTEM GMBH**, Bergisch Gladbach (DE)

(**) Term: **15 Years**

(21) Appl. No.: **29/802,711**

(22) Filed: **Aug. 6, 2021**

(51) LOC (14) Cl. **09-03**

(52) U.S. Cl.

USPC **D9/425**; D7/400

(58) **Field of Classification Search**

USPC D7/387, 397, 400, 399, 523, 647, 667;
